COMBINED CIGARETTE AND MATCHBOOK
CASE OR SIMILAR ARTICLE

Russell Eckenboy, Detroit, Mich.

Application August 18, 1949, Serial No. 4,589

Term of patent 14 years

(Cl. D85—2)

To all whom it may concern:

Be it known that I, Russell Eckenboy, a citizen of the United States of America, residing at Detroit, in the county of Wayne, and State of Michigan, have invented a new, original, and ornamental Design for a Combined Cigarette and Match Book Case or Similar Article, of which the following is a specification, reference being had to the accompanying drawing, forming a part thereof; wherein:

Figure 1 is a front perspective view of a combined cigarette and match book case or similar article, showing my new design;

I claim:

An ornamental design for a combined cigarette and match book case or similar article, substantially as shown and described.

RUSSELL ECKENBOY.
